DANIEL SANFORD REID, OF SILURIA, ALABAMA, ASSIGNOR OF ONE-HALF TO
WILLIAM F. STROWD, OF SILURIA, ALABAMA.

AUTOMATIC STOP FOR MOTION-PICTURE MACHINES.

1,419,759.

Specification of Letters Patent. Patented June 13, 1922.

Application filed May 17, 1921. Serial No. 470,384.

To all whom it may concern:

Be it known that I, DANIEL SANFORD REID, a citizen of the United States, residing at Siluria, in the county of Shelby and State 5 of Alabama, have invented new and useful Improvements in Automatic Stops for Motion-Picture Machines, of which the following is a specification.

This invention relates to control devices 10 for motion picture machines, particularly to automatic stops therefor, and has for its object the provision of a novel device which will be operated automatically in case of breaking of the film whereby to cut off the 15 motor which drives the film reeling mechanism and also to cut off the control switch leading to the light within the lamp house or lamp box.

An important object is the provision of 20 a control device of this character which includes a novel switch structure for controlling the two circuits, the one circuit to the lamp house and the other to the operating motor, both circuits being cut off simultaneously in the event of breaking of the film.

A further object is the provision of a device of this character including a movable member which normally engages the film during the travel of the latter and which is 30 spring pressed in the event of breaking of the film so as to actuate the control switch above mentioned.

An additional object is the provision of a device of this character which will be simple and inexpensive in manufacture and installation, highly efficient in use, not likely to get out of order, positive in action, durable in service and a general improvement in the art.

With the above and other objects and advantages in view, the invention consists in the details of construction to be hereinafter more fully described and claimed and illustrated in the accompanying drawings in 45 which—

Figure 1 is a side elevation of my device positioned upon a motion picture machine,

Figure 2 is a plan view of the device,

Figure 3 is a sectional view through the 50 control switch;

Figure 4 is a section at right angles to Figure 3,

Figure 5 is a view similar to Figure 3 showing the switch in circuit breaking position,

55

Figure 6 is a detail view of a latch device, and

Figure 7 is a diagrammatic view of the electric circuit.

Referring more particularly to the drawings, the letter A designates broadly the motion picture machine having the usual reeling mechanism, not shown, which serves to move along the strip of film B in association with the projector C. The letter D 65 designates the lamp house or lamp box within which is an electric illuminating means D' of the ordinary type. The letter E designates the motor which operates the reeling mechanism. The letter F designates a transformer of the usual type from which lead wires G which ordinarily conduct current to the electric lamp devices within the lamp house D. The feed wires to the electric motor are designated by the letter H and I designates a control switch for controlling the current to the motor E.

In carrying out my invention I provide a guide bracket 10 secured upon one side of the machine A by any suitable means and 80 at any desired location found convenient, one end of this bracket 10 being free and formed with a slot 11 and the other end being upturned to provide a support, as indicated at 12. Movable along the slot 11 is an 85 elongated lever 13 which has its upper end carrying a roller 14 bearing against the forward side of the film strip B. The numeral 15 designates a coil spring which is connected at one end with the lever above 90 the bracket and which has its other end connected with a hook 16 which extends through the upright support 12 and which has a threaded shank 17 carrying an adjusting nut 18. By means of this adjustable connection 95 it will be seen that the tension of the spring may be varied so as to regulate the spring in order that it will not have a greater tension than the tension of the film strip passing through the reeling mechanism.

In connection with the above described parts, I provide a switch device located at one side of the casing or machine A and this switch device includes a stationary cylin-

100

drical casing 19 carrying a plurality of contacts 20 and 21 with which are connected the wires G and H, respectively. Disposed within this stationary casing 19 is a rotary 5 spider-like element 22. This casing also carries contacts 23 and 24 which are opposite the contacts 20 and 21, respectively. The member 22 carries elements 22^a and 22^b adapted to connect the contacts 20 and 23, 10 and 21 and 24, respectively. Connected with the contacts 23 are wires 25 which lead to the electric lamp D' within the lamp house D, and connected with the contacts 24 are wires 26 which lead to the switch I which is 15 in turn connected with the motor E. The movable element 22 is carried upon a shaft 27 upon the free end of which is secured the lower end of the lever 13. The numeral 28 designates a suitable switch interposed in 20 the wires 25.

The operation of the device is as follows:

Under ordinary conditions, that is when the film B is running through the reeling mechanism in a normal condition, the tension upon the film strip will hold the lever 13 in normal position at the forward end of the slot 11 with the spring 15 held under tension. At this time the rotary element 22 of the control switch device is in such position that the elements 22^a and 22^b engage with the contacts 20 and 23, and the contacts 21 and 24 respectively, and the motor E for driving the reeling mechanism and the illuminating device, within the lamp house 30 D are both energized.

In the event that the strip of film B should break and the tension upon the roller 14 is consequently relieved, it will be apparent that the spring 15 will operate to 40 swing the lever 13 rearwardly and this will result in rocking of the shaft 27 and rotary member 22 and this will of course result in breaking the engagement of the elements 22^a and 22^b with the contacts 20 and 23 and 21 45 and 24. The instant that this occurs it will be apparent that the motor E and the illuminating device within the lamp house D will both be deenergized so that the entire motion picture machine will cease to operate.

Associated with the lever 13 is a suitably pivoted hook 30 which is engageable with the lever for holding the latter inactive when the operator desires to rethread the projecting machine after the strip of film has 50 been broken and the stop mechanism has been operated. When the hook is engaged with the lever 13 it will be readily apparent that the lever will not move. It is intended that the operator should disengage the hook 55 from the lever when the rethreading of the machine is accomplished, but in case the operator should forget to release it, it is 60 apparent that when the machine is started up the tension of the film passing over the

roller 14 will cause the lever 13 to be moved 65 forwardly to a slight extent whereupon the hook 30 will gravitationally drop and disengage itself from the lever 13.

From the foregoing description and a study of the drawings it will be apparent 70 that I have thus provided a very simple constructed and consequently inexpensive automatic stop mechanism which may be easily applied or installed and which operates very efficiently to stop the motion picture machine 75 in event of breaking of the film.

While I have shown and described the preferred embodiment of the invention, it is of course to be readily understood that I reserve the right to make such changes in the form, 80 construction and arrangement of parts as will not depart from the spirit of the invention or the scope of the subjoined claims.

What is claimed is:

1. In combination with the electric illuminating device and the operating motor of the reeling mechanism of a motion picture machine; an automatic stop device comprising a guide bracket secured upon the machine, a lever movable through the guide 90 bracket and carrying a roller normally engaging against the strip of film passing through the reeling mechanism, spring tension applied to said lever, the tension of the film being greater than the tension of the 95 spring whereby to hold the lever in normal position, and a switch mechanism operatively connected with the other end of said lever and adapted to be operated by movement of the latter, said switch mechanism 100 including a set of contacts connected with a source of current and with the illuminating device, a second set of contacts connected with a separate source of current and connected with the motor for actuating the film 105 winding mechanism, and third and fourth sets of contacts movably mounted and simultaneously engageable with the first and second named contacts respectively.

2. An automatic stop mechanism for motion picture machines, comprising a slotted guide bracket secured upon the side of a motion picture machine, a lever slidable along said bracket and carrying a roller engaging a strip of film passing through the reeling 115 mechanism of the machine, adjustable spring tension on said lever whereby to hold the same firmly in engagement with the strip of film, the tension of said spring being less than the tension of the strip of moving film, 120 a switch device including a stationary element, two sets of contacts carried by said element and connected with separate sources of current, and a movable element carrying two sets of contacts engageable 125 with said stationary contacts.

In testimony whereof I affix my signature.

DANIEL SANFORD REID.
